THREAD FEEDING MECHANISM FOR WARP
KNITTING MACHINES

Edward Kinsella, John Gordon Pratt, and Bernard Kelsall, Spondon, near Derby, England, assignors to Celanese Corporation of America, a corporation of Delaware

Application October 26, 1932, Serial No. 639,639
In Great Britain November 3, 1931

5 Claims. (Cl. 66—86)

This invention relates to mechanisms for feeding threads in textile machines, and is particularly concerned with the warp feeding means used in connection with warp knitting machines. It is an object of the invention to provide improved means for feeding warp threads to the needles in knitting machines of this kind and especially means capable of feeding the threads at a high rate.

10 According to the present invention a warp knitting machine comprises a source of supply of threads such as a beam, creel, or plurality of sectional beams, a series of needles adapted to perform knitting cycles and in the course of said cycles to draw thread intermittently from the supply, and a bar or other means which is positively actuated to draw thread from the supply in synchronism, but out of phase, with the thread-drawing movement of the knitting cycles and to release it in phase with such thread-drawing movement, for consumption by the needles. The beams or bobbins from which the threads are drawn are braked in order that threads may be tensioned, and the drawing of the threads therefrom is effected partly by the motion of the needles themselves, and partly by the motion of the thread-drawing means (hereafter referred to as a "bar"), the motion of the bar being preferably so timed and of such magnitude that by the 25 combined action of the needles and the bar, the threads are drawn away from the supply at a substantially constant rate.

The thread-drawing bar in advancing acts to deflect the threads as they pass from the supply to the guides, an increase in the deflection serving to pull the threads from the supply. At the same time, the needles are enabled to pull thread from the supply in their turn. Thus, when the needles move down to knit, a demand for threads is created which is satisfied partly by the thread-drawing action of the needles themselves, and partly by a thread-releasing motion of the positively actuated thread-drawing bar as it is retracted. Before the next thread-drawing motion of the needles, the thread-drawing bar is once more advanced in order to draw a further supply of thread from the supply. On lowering the needles again, the thread thus drawn off is released by an opposite, retractive motion of the bar, and supplied to the needles at the moment of demand, and so on. In this manner the bar is operated in synchronism with, but out of phase with, the thread-drawing motion of the needles, the time between the intervals during which the 55 needles themselves are drawing the thread being

occupied by a period in which the bar is drawing thread from the supply.

The device according to the invention is applicable to warp knitting machines generally, and is particularly advantageous in connection with the high speed warp knitting machine described in U. S. application Serial No. 639,638 filed Oct. 26, 1932 corresponding to British application No. 30500/31, filed November 3, 1931. The invention may be used in connection with any convenient 10 source of supply of warp threads, for example beams or sectional beams to which a braking effort is applied in order to tension the thread in the desired manner, it being preferable that the braking effort may be adjustable in accordance 15 with the varying diameter of the beam. Similarly, when the supply comes from a creel of bobbins, each bobbin may be separately braked. If, as is often the case in warp knitting machines, the threads are supplied to the needles in two 20 warp sheets, two thread-drawing bars are provided, one for each sheet, and positively driven by pairs of cams arranged side by side at the ends of the machine.

The invention will now be described in greater 25 detail with reference to the accompanying drawing, but it is to be understood that this description is given by way of example only, and is in no way limitative.

In the drawing: 30
Fig. 1 is a sectional view of one end of the machine;

Fig. 2 is a part plan taken on the line 2—2 of Fig. 1; and

Fig. 3 shows a detail of the mechanism. 35

The two sets of warps 4, 5 are supplied with beams 6, 7 carried on brackets 8 mounted on the upper side of the machine frame 9. Each warp beam is provided with a brake drum 10 so that tension of the warps can be adjusted by the use 40 of suitable weights 11 carried by brake bands 12 passing round the brake drums.

Each sheet of warps passes over its own drawing bar 13, 14 before travelling substantially vertically downwards to the thread guides 15. 45 The bars 13, 14, which are preferably tubular so as to be of minimum weight consistent with rigidity, are carried by levers 16 suspended from the brackets 8 and connected by links 17 to cam-follower levers 18 pivoted at 19 on the frame 9. 50 Each lever 18 carries a cam follower 20 to follow its cam 21. The two cams 21 are secured to a shaft 22 on which is mounted a chain wheel 23 geared by a chain 24 to a sprocket 25 on the main cam-shaft 26 of the machine. The cams 21 are so po- 1

sitioned with respect to the cam-shaft 26 that the bars 13, 14 are advanced so as to deflect the warps 4, 5 after the needles 27 have completed their thread-drawing movement and while the last 5 row of knitted loops is being drawn from the needles by the pull of the take-up device 28. This deflection causes thread to be drawn from the beams 6, 7 substantially continuously, while on the retraction of the bars 13, 14 a supply of thread 10 is available to be wrapped round the needles 27 on their next knitting movement. In this way, the thread can be drawn from the beams 6, 7 at a substantially constant rate, and the mechanism is relieved from the strain imposed when the relatively heavy beams have to be rotated intermittently.

It is convenient to have the cams 21 effect two thread-drawing movements for each revolution while the main cam-shaft 26 carries out one knitting movement for each revolution. The cams 21 are therefore made with two lifts, and a 2:1 reduction gear drives the auxiliary cam-shaft 22 from the main shaft 26. Each lift of each cam is, of course, suitably profiled in accordance 20 with the exact requirements of the particular lapping to be effected at the needles at the time it is in operation.

As is clear from the drawing, the weight of the bars 13, 14 and the associated links and levers acts in conjunction with the tension in the warps 4, 5 to press the followers 20 firmly against the cams 21 so that the thread-drawing and releasing movements of the bars 13, 14 are accurately controlled.

35 It will be understood that both ends of the bars 13, 14 are driven by similar pairs of cams 21 acting in synchronism and similarly driven from the cam-shaft 26.

What we claim and desire to secure by Letters 40 Patent is:—

1. A warp knitting machine comprising a source of supply of warp threads, a series of needles for performing knitting cycles and adapted, in the course of such cycles, to draw thread intermittently from said supply, means for actuating said needles in said knitting cycles, thread-drawing means adapted to draw thread from the supply, and means for actuating said thread-drawing means in synchronism with said needles to draw thread from the supply out of phase 45 with the thread-drawing movements of the needles, and to release it in phase with such thread-drawing movements to satisfy in part the thread-drawing action of the needles.

55 2. A warp knitting machine comprising a source of supply of warp threads, a series of needles for performing knitting cycles and adapted, in the course of such cycles, to draw threads intermittently from said supply, means for actuating said needles in said knitting cycles, thread-drawing means adapted to draw thread from the supply, and means for actuating said thread-drawing means in synchronism with said needles to draw thread from the supply out of phase 60 with the thread-drawing movements of the needles, and to release it in phase with such thread-drawing movements to satisfy in part the thread-drawing action of the needles.

65 dles to draw thread from the supply out of phase with the thread-drawing movements of the needles, and to release it in phase with such thread-drawing movements to satisfy in part the thread-drawing action of the needles, the rate of drawing and releasing of thread by said thread-drawing means being such as to render substantially constant the rate at which thread is drawn from the supply by the combined action of the needles and the thread-drawing means.

70 3. A warp knitting machine comprising a source of supply of warp threads, a series of needles for performing knitting cycles and adapted, in the course of such cycles, to draw thread intermittently from said supply, means for actuating said needles in said knitting cycles, a thread-drawing bar adapted to draw thread from the supply, and means for actuating said bar in synchronism with said needles to draw thread from the supply out of phase with the thread-drawing movements of the needles, and to release it in phase with such thread-drawing movements to satisfy in part the thread-drawing action of the needles.

75 4. A warp knitting machine comprising a source of supply of warp threads, a series of needles for performing knitting cycles and adapted, in the course of such cycles, to draw thread intermittently from said supply, means for actuating said needles in said knitting cycles, a thread-drawing bar adapted to draw thread from the supply, and means for actuating said bar in synchronism with said needles to draw thread from the supply out of phase with the thread-drawing movements of the needles and to release it in phase with such thread-drawing movements to satisfy in part the thread-drawing action of the needles, the rate of drawing and releasing of thread by said bar being such as to render substantially constant the rate at which thread is drawn from the supply by the combined action of the needles and the bar.

80 5. A warp knitting machine comprising a source of supply of warp threads, a series of needles for performing knitting cycles and adapted, in the course of such cycles, to draw thread intermittently from said supply, cam means adapted to actuate said needles to perform said cycles, a thread-drawing bar over which the threads pass in proceeding from the supply to the needles, and cam means rotating synchronously with said knitting cam means and kept in driving connection with said bar by the weight of the bar and the tension in the threads, said cam means being adapted to advance and retract said bar, to cause it to draw thread from the supply out of phase 85 with the thread-drawing movements of the needles, and to release it in phase with such thread-drawing movements to satisfy in part the thread-drawing action of the needles.
